FRICITION MECHANISM FOR CAR TRUCKS

James A. Shafer, East Cleveland, Ohio, assignor
to National Malleable and Steel Castings Company,
Cleveland, Ohio, a corporation of Ohio

Application June 27, 1936, Serial No. 87,674

20 Claims. (Cl. 105—197)

My invention relates to railway car trucks and has for an object the provision of novel means for effectively preventing harmonic vibrations of the bolster supporting springs. In this connection the invention provides means simple in construction and reliable in action for snubbing oscillations of said springs and thus preventing the occurrence of undesirable vibrations. The invention has been developed in conjunction with 5 car trucks of the type shown in my Patent No. 1,973,664, and is of particular utility with such trucks, enabling the retention of the advantages thereof while at the same time insuring in a novel manner the elimination of undesired spring 10 oscillation.

A further object is the provision of snubbing or damping means which may be incorporated in car trucks of the type shown in said Patent No. 1,973,664 without necessitating any change 20 in the construction of the bolster or side frame thereof, whereby such snubbing means can be applied to trucks of this type already in service.

An important feature of my invention is the utilization of the walls of the bolster spring 25 pockets as a housing or friction casing, thus obviating the need of a separate casting to perform this function. By making use of the bolster pocket construction peculiar to this type of truck, an exceptionally strong and rigid friction housing 30 is obtained whereby the danger of cracking and breaking is materially reduced. Furthermore, due to the employment of the inverted bolster pockets to receive and enclose the snubbing device, and due to the particular location 35 of such pockets in this type of truck, such location being appreciably higher than that of the bolster springs in the conventional type of truck, the possibility of water and brine from refrigerator cars getting into the snubbing device and 40 contacting the friction surfaces thereof is considerably diminished, and its consequent deteriorating effect on such surfaces eliminated.

A more specific object of my invention is the provision of rockers held in assembled relation 45 with the bolster and certain of the bolster supporting springs, said rockers being adapted to cooperate with the friction housing of the bolster to form the snubbing means referred to above. By locating the friction arms of the rockers outside of the coil springs mounted thereon, an exceptionally large frictional bearing area is obtained, thereby insuring longer life of the friction parts by reason of decreased unit pressure.

Another particular object of my invention is 55 the provision of wear shoes adapted to be received

within the friction housing of the bolster and cooperating with the rocker arms mentioned above to obviate any wear on the bolster.

A further feature of my invention is the provision of interlocking means between the rockers, 5 wear shoes, and bolster, whereby said rockers and wear shoes are locked against rotation within their respective friction housings.

These and other features and objects of my invention will become more apparent from the 10 following detailed description and the appended claims.

In the accompanying drawings:

Figure 1 is a side elevation, partly in section, 15 of a car truck embodying my invention, the bolster and associated parts being shown in section through the front springs.

Figure 2 is a transverse vertical sectional view on the line 2—2 of Fig. 1.

Figure 3 is a horizontal sectional view on the 20 line 3—3 of Fig. 2.

Figure 4 is an isometric view of one of the 25 rocker arms; and

Figure 5 is an isometric view of one of the wear shoes.

Referring more particularly to the drawings, there is shown at A a portion of a side frame of a car truck having a window 2 for the reception of a bolster B. The side frame illustrated is of the type shown in my patent above referred 30 to, being formed below the window with a portion designated generally by the numeral 3, within which springs 4, 5 are adapted to be seated and housed, said portion 3 comprising a bottom shelf 6, a top flange or shelf 7, and side walls 8, 9. Said 35 side walls are integral with said shelves 6, 7 and also with the side walls 10 of the inclined tension members C. It will, of course, be understood that a similar side frame cooperates with the opposite end of the bolster B, but for the purposes of the 40 present invention a consideration of the cooperation between one side frame and the bolster B will be sufficient.

Each end of the bolster B is formed with a pair of downwardly opening housings or pockets 12, 45 13 separated by a dividing wall 14. Dowels or projections 15 integral with the bolster extend downwardly therefrom, through openings 16 in the shelf 7, for engagement with spring caps 17 on the lower springs 4, 5. These dowels 15, two of 50 which are provided on each end of the bolster, further serve to tie the two side frames of the truck together in the same manner as do the corresponding bolster dowels in the previously mentioned patent.

Received within the pockets 12, 13 of the bolster are sets of springs 18, 19 each set being supported on a pair of rockers 20, 20. The springs 18, 19 and rockers 20 are retained within their respective bolster pockets by means of the bolts 21 and nuts 22, which are received within suitable openings in the horizontal arm 23 of each rocker. It will be noted that this arm 23 is provided with an upwardly offset portion 23' forming a recess 22' to receive the nut 22. This offset portion further serves to center the outer coils of the spring group supported by the rocker, and also acts as a seat for the innermost coil of such spring group. Each rocker is also provided with a vertical arm 24 arcuate in cross-section so as to conform to the contour of the side walls 25, 26 of the bolster pockets 12, 13. These side walls 25, 26 are circular in cross-section over a considerable portion of their extent, but adjacent the dividing wall 14 each wall curves in the opposite direction from said circular portions to form pockets or recesses 27 for a purpose to be later described. The under side of the horizontal arm 23 of each rocker 20 is formed with a flattened surface 28 and an upwardly tapering portion 29 thereby presenting, in effect, a fulcrum point 30 about which the rocker is adapted to pivot or rotate. The upper surface of this arm is formed with recesses 31, 31 whereby the major portion of the spring load on said arm will be applied outwardly of the fulcrum point 30. The spring load will therefore tend to rotate the rockers outwardly so that the vertical arms 24 will be pressed into frictional engagement with the bolster pocket side walls 25, 26. Upon relative vertical movement between the bolster and the rockers, friction will accordingly be generated therebetween for snubbing the oscillations of the bolster supporting springs. The friction developed by the snubbing device may be varied by moving the fulcrum point 30 of the rockers inwardly or outwardly, thus changing the lever arms to increase or decrease the snubbing action as desired.

Although I prefer to interpose wear shoes 32, 32 between the bolster pocket side walls and the vertical arms of the rockers for the purpose of eliminating wear on the bolster, it will be understood that, if desired, these arms may directly engage the side walls. The wear shoes 32, 32 which I have provided within the bolster pockets each consist of a horizontal base portion 33 overlying the springs within said pocket, and a downwardly extending wear flange 34 of approximately the same vertical extent as the bolster pocket side walls. This flange, like the vertical arms of the rockers, is arcuate in cross-section to conform to the curvature of the circular portions of the bolster pocket walls against which the flange is adapted to seat. Flange 34 thereby presents a friction surface for engagement with the friction surface on the vertical arms of the rockers.

It will be observed that the bolster pocket walls are not entirely circular in contour, nor of uniform vertical extent throughout. Consequently, if the wear shoes were free to rotate within their respective pockets, a condition might arise wherein the depending flanges 34 would not be properly supported by the bolster walls. Under such a condition the pressure of the vertical arms of the rockers against the unsupported flange might result in the breaking thereof and the consequent rendering of the mechanism inoperative. To obviate this I have provided novel locking means for the wear shoes and rockers whereby any appreciable rotative movement of such parts within

their respective bolster pockets is effectively prevented.

Referring particularly to Figs. 4 and 5, it will be noted that the depending flange 34 of the wear shoe is of lesser vertical extent at each side thereof, as shown at 34', than the central portion of the flange, thus forming recessed or cut-away portions. Projections 35, 35 at each side of the rocker 20 are adapted to be received within these recessed portions of the flange 34, sufficient clearance being provided between the top surfaces 36, 36 of these projections and the under surfaces 37, 37 of the portions 34' of the flange to permit the bolster supporting springs to be fully compressed. As will be clearly seen in Fig. 3, the projections 35 present abutment shoulders 38, 38 in close proximity to the edges or shoulders 39, 39 of the depending flange 34 of the wear shoe and cooperating therewith to limit rotation of the rocker with respect to its associated shoe. To lock the wear shoe with the bolster a lug or projection 40 is formed on the exterior surface of the flange 34 at one side only and just above the recessed portion thereof. This lug 40 extends into the recess 27 in the bolster pocket and engages the adjacent bolster walls to limit rotation of the wear shoe in the bolster pocket. Thus it will be understood that the rockers 20 and wear shoes 32 are both locked against any appreciable rotation within the bolster pockets.

Although I have illustrated my novel snubbing arrangement applied to both pockets 12, 13 in each end of the bolster, it will be understood that such arrangement may be applied to only one of these pockets, and the usual coil springs applied to the other, if so desired. It may be that for certain purposes a single snubbing device will provide sufficient absorption to prevent undesired spring oscillation.

From the above description it will be seen that I have invented novel snubbing means, simple in construction and reliable in action, for freight car trucks, said means being compact in arrangement and adapted to be assembled entirely within the bolster before its application to the side frames, thereby forming a unitary structure with the bolster. Furthermore my snubbing means may be readily applied to trucks of the type disclosed in my patent above mentioned which are already in service without necessitating any change whatever in the construction of the side frame or bolster.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a car truck, a side frame, a bolster, a downwardly opening pocket in the end of said bolster, vertically disposed spring means within said pocket for supporting said bolster, and means on said side frame for supporting said spring means and exerting outward pressure against the side walls of said bolster pocket under the influence of said spring means.
2. In a car truck, a side frame, a bolster, a downwardly opening pocket in the end of said bolster, vertically disposed spring means within said pocket for supporting said bolster, and means on said side frame and adapted to be received within said pocket for supporting said

- spring means and exerting outward pressure against the side walls of said bolster pocket under the influence of said spring means.
3. In a car truck, a side frame, a bolster, a downwardly opening pocket in the end of said bolster, a pair of rocker members on said side frame and adapted to be received within said pocket, and bolster supporting spring means within said pocket and carried by said members for causing said members to exert outward pressure against the side walls of said bolster pocket.
4. In a car truck, a side frame, a bolster, a downwardly opening pocket in the end of said bolster, spring means within said pocket for supporting said bolster, and snubbing means for said spring means comprising a pair of rocker members on said side frame, said rocker members having horizontal arms extending under said spring means and vertical arms forced by said springs to exert outward pressure against the side walls of said bolster pocket.
5. In a car truck, a side frame, a bolster, a downwardly opening pocket in the end of said bolster, spring means within said pocket for supporting said bolster, and snubbing means for said spring means comprising a pair of rocker members on said side frame and adapted to be received within said pocket, said rocker members having horizontal arms extending under said spring means and vertical arms forced by said spring means to exert outward pressure against the side walls of said bolster pocket.
6. In a car truck, a side frame, a bolster, a downwardly opening pocket in the end of said bolster, rocker members each pivotally mounted at one of its ends on said side frame, and bolster supporting spring means within said pocket and carried by said members for causing said members to exert outward pressure against the side walls of said bolster pocket.
7. In a car truck, a side frame, a bolster having a downwardly opening pocket at the end thereof, the walls of said pocket being circular in section over a portion of their extent, spring means within said pocket for supporting said bolster, and snubbing means for said spring means comprising a pair of rocker members pivotally mounted on said side frame, said rocker members having horizontal arms extending under said spring means and vertical arms circular in section for cooperation with the circular portion of said walls under the influence of said springs.
8. In a car truck, a side frame, a bolster having a downwardly opening pocket at the end thereof, the walls of said pocket being circular in section over a portion of their extent, spring means within said pocket for supporting said bolster, snubbing means for said spring means comprising a pair of rocker members pivotally mounted on said side frame, said rocker members having horizontal arms extending under said spring means and vertical arms circular in section for cooperation with the circular portion of said walls, and means for maintaining said members against rotation within said pocket.
9. In a car truck, a side frame, a bolster having a downwardly opening pocket at the end thereof, wear shoes within said pocket, spring means between said shoes and cooperating therewith to hold the shoes in said pocket, and snubbing means for said spring means comprising a pair of rocker members pivotally mounted on said side frame, said rocker members having horizontal arms extending under said spring means and vertical arms adapted to frictionally engage said wear shoes under the influence of said springs.
10. In a car truck, a side frame, a bolster having a downwardly opening pocket at the end thereof, the walls of said pocket being circular in section over a portion of their extent, spring means within said pocket for supporting the bolster, snubbing means for said spring means including a rocker member pivotally mounted on said side frame, a wear shoe in said pocket, said rocker member and wear shoe having vertically extending arms circular in section and adapted to frictionally engage with each other under the influence of said spring means and means on said arms for locking said rocker member and wear shoe against rotation with respect to each other.
11. In a car truck, a side frame, a bolster having a downwardly opening pocket at the end thereof, the walls of said pocket being circular in section over a portion of their extent, spring means in said pocket for supporting the bolster, snubbing means for said spring means including a rocker member pivotally mounted on said side frame in said pocket, said rocker member and wear shoe having vertically extending arms circular in section and adapted to frictionally engage with each other under the influence of said spring means, and means for locking said rocker member and wear shoe against rotation with respect to each other including a projection on said rocker member and a shoulder on said wear shoe.
12. In a car truck, a side frame, a bolster having a downwardly opening pocket at the end thereof, the walls of said pocket being circular in section over a portion of their extent, spring means in said pocket for supporting the bolster, snubbing means for said spring means including a rocker member pivotally mounted on said side frame, a wear shoe in said pocket, said rocker member and wear shoe having vertically extending arms circular in section and adapted to frictionally engage with each other under the influence of said spring means, and means on said arms for locking said rocker member and wear shoe against rotation within said pocket comprising projections on said rocker member for cooperation with shoulders on said wear shoe and a lug on said wear shoe received in a recess in said pocket.
13. In a car truck, a side frame having a bolster receiving opening and a shelf therebelow, a bolster extending into said opening and formed with a downwardly opening pocket in the end thereof, spring means on said side frame above and below said shelf for supporting said bolster, the upper spring means being adapted to be received in the said pocket, and snubbing means comprising rockers pivotally mounted on said shelf for frictionally engaging the inner sides of the walls of said pocket under the influence of said springs.
14. In a car truck, a side frame having a bolster receiving opening and a shelf therebelow, a bolster extending into said opening and formed with a downwardly opening pocket in the end thereof, spring means on said side frame above and below said shelf for supporting said bolster, the upper spring means being adapted to be received in the said pocket, and snubbing means on said shelf for supporting said upper spring means and exerting outward pressure against the walls of said pocket under the influence of said upper spring means.
15. In a car truck, a side frame having a bol-

- ster receiving opening and a shelf therebelow, a bolster extending into said opening and formed with a downwardly opening pocket in the end thereof, spring means on said side frame above and below said shelf for supporting said bolster, the upper spring means being adapted to be received in the said pocket, wear shoes within said pocket, and snubbing means for said springs comprising rockers pivotally mounted on said side frame, said rockers having horizontal arms extending under said upper spring means and vertical arms adapted to exert an outward pressure against the wear shoes under the influence of said upper spring means.
- 15 16. A car truck bolster having a downwardly opening hollow end portion, spring means in said portion, wear shoes positioned outwardly of said spring means and retained within said portion thereby, rocker members having extensions underlying said spring means and vertically extending portions for frictional engagement with said wear shoes, and means maintaining said rocker members, wear shoes and said springs in vertically assembled relation to said bolster.
- 20 17. A car truck bolster having a downwardly opening hollow end portion, the walls of said opening being circular over a portion of their extent, means in said portion, rocker members having extensions underlying said spring means and vertical portions circular in section for cooperation with the circular portions of said walls, and means for locking said rocker members against rotation within said opening.
- 25 18. A car truck bolster having a downwardly opening hollow end portion, the walls of said

opening being circular over a portion of their extent, spring means in said portion, rocker members having extensions underlying said spring means and vertical portions circular in section for cooperation with the circular portions of said walls, means for locking said rocker members against rotation within said opening and other means maintaining said rocker members and said springs in vertically assembled relation to said bolster.

10 19. In a car truck, a side frame, a bolster, a downwardly opening pocket in the end of said bolster, rocker members pivotally mounted at one end thereof on said side frame, bolster supporting spring means within said pocket and carried by said members for causing said members to exert outward pressure against the side walls of said bolster pocket, and means on said rocker members for confining the engagement between said spring means and rocker members to portions of said members spaced outwardly from the pivots thereof.

15 20. In a car truck, a side frame, a bolster, a downwardly opening pocket in the end of said bolster, rocker members pivotally mounted at one end thereof on said side frame, bolster supporting spring means within said pocket and carried by said members for causing said members to exert outward pressure against the side walls of said bolster pocket, said rocker members being formed with cut-away portions for confining the engagement between said spring means and rocker members to portions of said members spaced outwardly from the pivots thereof.
